UNITED STATES PATENT OFFICE

ELIZABETH JANE HARING, OF SPOKANE, WASHINGTON

PORTABLE BATHTUB EQUIPMENT

Application filed August 7, 1931. Serial No. 555,708.

My present invention relates to an improved portable bathtub equipment designed especially for use in bathing infants and babies, but of course equally adapted for use when bathing small domestic or household pets. The primary object of the invention is the provision of a portable apparatus including essentially a flexible bath tub in which the baby may be bathed with comfort and safety, and a table for convenience of the mother, nurse, or other attendant who administers the bath to the child.

The table is preferably of the foldable type, and the flexible tub and its accessories are of such construction as will permit the equipment to be folded into compact form for storage purposes when not in use.

The invention consists in certain novel combinations and arrangements of parts as will hereinafter be more fully set forth and claimed. In the accompanying drawing I have illustrated one complete example of the physical embodiment of my invention wherein the parts are combined and arranged according to the best mode I have thus far devised for the practical application of the principles of my invention.

Figure 1 is a perspective view of the portable bathing equipment, set up and ready for use in a standard household or domestic bath tub.

Figure 2 is an enlarged, vertical, transverse sectional view through the table top, the flexible bath tub, and the apron, the latter shown in position for use as an auxiliary rest or flexible pad for supporting the baby after the bath, and while dressing it.

Figure 3 is a sectional detail view showing the manner of fastening or anchoring the reinforced, cushioned rim of the flexible tub to the table top, and showing also one of the snap fasteners for the apron when it is used as a dressing pad, after the bath.

Figure 4 is a view in section of a portion of the flexible tub showing the draining features.

Figure 5 is an enlarged view showing a rubber ferrule on one of the table legs for safety, and to prevent scratching or marring by the table legs.

In Figure 1 a preferred manner is illustrated for using the equipment, in connection with the usual domestic bathtub 1 that is provided with faucets F where water may conveniently be obtained for the bath, but it will be apparent that the portable equipment may be employed in other ways in the performance of various functions.

In carrying out my invention I utilize a table, here shown as rectangular in shape, and of proper height to bring its top 2 up to a level that is convenient for use by the nurse or mother when bathing a child, and the size and shape of the table are preferably such that will permit its use in the standard size bath tub 1, as indicated in Figure 1. The four legs 3 of the table are foldable, and braced by the usual pivoted links 4 between the table top and the legs, and the feet of the legs are preferably provided with rubber ferrules 5 to prevent the legs from slipping and to prevent scratching or marring of the surface of the tub 1.

The top 2 of the table is preferably of sheet metal, and enameled for sanitary purposes, and the top, which is provided with an edge flange 6 for reinforcement, is fashioned with an opening whose edges are countersunk as at 7, and these countersunk edges are fashioned with a depressed, grooved rim or flange 8. The flexible bath tub 9 is of generally rectangular shape and is suspended within the complementary opening of the table top, and the tub may be fashioned from suitable material as rubber, rubberized fabric, and similar goods.

Near the rim of the flexible tub its side walls are thickened as at 10 to form a cushion for comfort and safety to the child, and also for the purpose of insuring a semi-rigid anchoring support for the body of the tub that will assist in maintaining the shape of the tube to prevent its wobbling. The weight of the baby places the walls of the tub under tension, and these semi-rigid anchoring supports for the walls of the tub hold the latter suspended in position so that the baby may sit upright notwithstanding the flexibility of the walls of the tub, and should the baby topple over from either side, or for-

ward or backward, the cushioned walls provide a soft and harmless impact for the safety of the child.

The thickened rim 11 of the flexible tub 5 and the cushioned side walls 10 are reinforced by the use of wire mesh as 12 embedded therein for the purpose of stiffening these parts, and a wire band 13 is also encased within the rim near its edge. As best 10 seen in Figure 3 the wire band forms a bead 14 in the rim that extends around the four sides of the rim, and the lower ridge of this bead is seated in the grooved or depressed flange 8 surrounding the opening in the table 15 top.

The stiffened rim of the flexible tub lies flat on the countersunk edges 7 and the grooves 8 of the table top, and a suitable number of fastening bolts 15 are passed through 20 holes in the table and stiffened rim, which, together with the nuts 16 threaded on the bolts against the underside of the table top, and the circular gaskets 17 on top of the rim of the flexible tub, firmly anchor or 25 fasten the stiffened rim on the table top. The bead 14, fitting snugly in the groove 8, relieves the rim of some of the strain due to the weight of the body in the tub, and assists in holding the tub in correct position and 30 proper shape.

The heads 18 of the bolts, are rounded, as shown, and project above the gaskets 17, for the purpose to be described.

At the bottom of the flexible tub an outlet, 35 or drain thimble or sleeve 19 is provided, and the screw plug 20, which is anchored to the exterior of the tub by means of the chain 21, is withdrawn from the thimble 19 when it is desired to drain the tub. As seen in 40 Figure 4 the drain thimble and plug are surrounded by the material of the tub, through the use of an exterior offset in the wall of the tub, for the purpose of preventing contact of the body with the metal parts.

45 A detachable apron 22, of material similar to that of the flexible tub, of rectangular shape, and with an opening therein complementary to the open top of the tub, is provided with socket-members 23, around its 50 outer edge, around its edge-opening, and transversely across its intermediate portion adjacent the opening. These socket members 23 are designed to snap over the rounded heads 18 of the bolts, in order that the open 55 end of the apron may be attached or fastened to the tub and table, as indicated in Figures 1 and 3, leaving the apron to hang as indicated in Figure 1 at the side of the table. This hanging or flap portion of the 60 apron in Figure 1 may be hung with its lower free end inside the tub 1, for use as a shield, when the plug 20 is withdrawn and the flexible tub is being drained.

65 After the bath, the flap portion of the apron 22 is turned up and folded over paral-

lel with the top of the table, and the free edges of the folded portion of the apron are fastened on the heads 18 by the use of the socket members 23. In this position the apron covers the open top of the tub and forms a flexible pad on which the baby may be laid for towelling and dressing. The flexible apron is depressed under the weight of the baby, and sags, as indicated in Figure 2 by dotted lines, to form a slight or shallow receptacle 70 that will prevent the baby rolling off the pad, or otherwise injuring itself by squirming upon the yieldable pad. The metal table top 75 2 at the right of the pad, in Figure 1 may be used to receive the clothing, soap, toilet articles, and other accessories, and they are thus 80 readily accessible when required.

While I have shown the portable bath tub used in connection with the stationary bath tub, it will be understood that the table and 85 flexible tub form a portable unit that may be folded into compact form for traveling, motoring, camping, or visiting, and the equipment may be set up for use in any 90 convenient place.

Having thus fully described my invention, what I claim, as new and desire to secure by Letters Patent is: —

1. In a portable bathing apparatus the combination with a table having a top and an 95 opening therein, of a flexible bathtub having stiffened edges, means for fastening said edges to the table top, an apron having an opening therein, and means on the apron for co-operation with said fastening means for 100 attaching the apron about the opening of the bath tub.

2. In a portable bathing apparatus, the combination with a table having a top and an 105 opening therein, of a flexible bath tub having stiffened edges, fastening bolts for securing said edges to the table top, fastening heads on the bolts, an apron having an opening complementary to the opening of the 110 tub, and fastening members on the apron for co-operation with said fastening heads whereby the apron may be attached in folded position or in unfolded position.

In testimony whereof I affix my signature.

ELIZABETH JANE HARING.
